US0D1092232S

(12) **United States Design Patent** (10) Patent No.: **US D1,092,232 S**
(45) Date of Patent: ** Sep. 9, 2025

(54) **PACKAGING CONTAINER**

(71) Applicant: **Lumielin International Inc.**, Tokyo (JP)

(72) Inventor: **Satoshi Kan**, Tokyo (JP)

(73) Assignee: **LUMIELINA INTERNATIONAL INC.**, Tokyo (JP)

(**) Term: **15 Years**

(21) Appl. No.: **35/522,533**

(22) Filed: **Oct. 4, 2023**

(80) **Hague Agreement Data**

Int. Filing Date: **Oct. 4, 2023**

Int. Reg. No.: **DM/232273**

Int. Reg. Date: **Oct. 4, 2023**

Int. Reg. Pub. Date: **Oct. 4, 2024**

(30) **Foreign Application Priority Data**

Apr. 6, 2023 (JP) ..... 2023-007163 D
